UNITED STATES PATENT OFFICE.

JOHN L. L. KNOX, OF ALLEGHENY, PENNSYLVANIA.

PNEUMATIC RAILROAD-SIGNAL.

SPECIFICATION forming part of Letters Patent No. 323,428, dated August 4, 1885.

Application filed May 5, 1885. (No model.)

To all whom it may concern:

Be it known that I, JOHN L. L. KNOX, a citizen of the United States, and a resident of Allegheny, in the county of Allegheny and State of Pennsylvania, have invented certain new and useful Improvements in Pneumatic Railroad-Signals, of which the following is a full, clear, and exact description.

My invention relates to that class of signals in which when a train enters upon a section the danger-signal facing opposite the direction of movement at the rear of the section is exposed, and at the same time the danger-signal facing in the direction of movement at the front extremity of the section is also exposed, while the corresponding signals of the section over which the train has already passed are simultaneously concealed.

The objects of the invention are, first, to simplify and compact the pump and signal-moving apparatus; second, to dispense with branch pipes; third, to simplify the mechanism which works the pumps, and at the same time insure the return of said mechanism to normal position after each movement; and, fourth, to render the movement of the signals certain and uniform.

The invention consists in the hereinafter-described means for attaining said objects.

In the drawings, Figure 1, Sheet 1, represents a top plan view of my invention, with signal-box removed; Fig. 2, Sheet 2, a side elevation of my invention; Fig. 3, Sheet 2, a plan view of the top of the pump, showing the ports; Fig. 4, Sheet 1, a longitudinal section of same on line A B of Fig. 3; Fig. 5, Sheet 1, a transverse vertical section of same on line C D of Fig. 3; Fig. 6, Sheet 2, a horizontal section of the casing containing the valves and signal mechanism; Fig. 7, a detail top plan view of one of the suction-valves; Fig. 8, a section of same on line G H of Fig. 7, showing the valve-locks; Fig. 9, a section of same on line I J of Fig. 7; Fig. 10, a detail top plan view of one of the forcing or pressure valves; Fig. 11, a longitudinal median section of same on line E F of Fig. 10; Fig. 11^a, a side elevation of the locks of the forcing-valves; Fig. 12, a detail view of the reciprocating rod and bifurcated lever by which the valve-stops are operated; Fig. 13, a horizontal section of the

signal-box on line K L of Fig. 2; Fig. 14, a detail view of the safety-valve; Fig. 15, a rear elevation of the tappet; Fig. 16, an edge view of same; Fig. 17, a front elevation of same. 55

Similar figures of reference indicate corresponding parts throughout the different views.

1 is the track-rail, supposedly at the beginning of one section of the road.

Secured to the road-bed or ties in any suitable manner, and in close proximity to the rail, is a bed-plate, 2, to which is bolted the bearing 3 for one end of a shaft, 4. A second bed-plate, 5, carries the bearing 6 of the other extremity of said shaft, the latter being 65 at right angles to rail 1.

Fixed to that end of shaft 4 which lies nearest the rail 1 is a tappet, 7, of ovoid outline, whose top normally extends some distance above said rail. Said tappet 7 is cut away 70 upon the outer side beneath the top at 8, in order that, when depressed, it shall not come in contact with the flange of the rail.

Midway of shaft 4 is secured a cross-piece, 9, whose extremities are fastened to links 10. 75 The latter are bolted to shackles, which embrace two ordinary elliptic springs, 11. The object of this construction is to force tappet 7 (and the pump mechanism) back to normal position after having been actuated by the 80 wheel of a passing car.

Attached to the extremity of shaft 4 beyond bearing 6 is a crank-arm, 12, to which is secured the pitman 13. The free extremity of said pitman is secured to the piston-rod 14 of 85 the pump 15. The casing of said pump is U-shaped, and provided at the ends of the top plate with four ports, 15^a 15^b 15^c 15^d. The ports 15^a and 15^b are connected with the chamber 16, and the ports 15^c 15^d in like manner 90 communicate with chamber 17. Within said chambers work the wings or pistons 18 19, by which the signal is operated. The walls of the chambers 16 17 may all be cast in a single piece. 95

The chambers 16 17 have each an end and two sides at right angles, and the remaining end curved through a quadrant whose radius is substantially identical with the length of the wings or pistons 18 19. Said curvatures 100 are diagonally opposite each other. The chamber 16 is somewhat larger than 17, in order

that the shafts of the valve-locking arms may not interfere, as will be hereinafter more fully explained. The pistons 18 19 are mounted on vertical shafts 20 21, respectively. Stops 22, 5 formed on the casting and within the paths of the pistons, limit the movement of the latter and prevent them from passing beyond the ends of the quarter-circle, hereinbefore described. The rotation of the pistons through 10 a quarter-circle is sufficient to move the targets 23 24 the required distance to exhibit them through the openings 23^a 24^a at "danger," or conceal them, as the case may require.

15 At that part of each chamber-casing which corresponds to the ends of the paths of the pistons 18 19 are slight recesses 25, and at one extremity of each chamber is a small opening, 26, communicating with the open air. The 20 object of this construction is to prevent the pistons cushioning upon the confined air, and also to avoid the vibration or "wabbling" of the target. The shafts 20 21 pass upward to the signal-box 27, and have bearings in the 25 top of it. Said box is elliptical in shape and contains two rotating targets, 23 24, each of which is arc-shaped, (preferably one-third of a circle,) and covers one of the openings 23^a 24^a when given a quarter-revolution.

30 By constructing the box and target as described I insure the proper exhibition of the target when the signal is set for "danger." The targets are mounted upon arms 29, which are secured to the shafts 20 21, so that any 35 movement of the pistons 18 19 causes the targets to turn in the proper direction.

Attached to the main shaft 4 upon the inside of the bearing 6 is a crank-arm, 30, which 40 operates a pitman, 31. Said pitman has its free extremity hinged to a rod, 32, which reciprocates in bearings secured to or made integral with the pump-casing. Said rod is provided with pins 33 34 on the side next the pump-casing.

45 35 36 are two rocking shafts, which extend transversely through the valve-chambers. Outside of said chambers the rocking shaft 35 is provided with a bifurcated lever, 35^a, whose legs 35^b 35^c straddle the pin 33, and the shaft 36 is provided with a bifurcated lever, 36^a, whose legs 36^b 36^c straddle the pin 34. Within the valve-chamber the shafts 35 36 are each provided with two arms, 37 37^a, having friction-rollers journaled in their extremities. 50 One of these arms upon each shaft is adapted, when vertical, to rest upon the extensions of and lock the suction-valves 38 39, and the other arm is adapted to rest upon the bodies of and lock the forcing-valves 40 41. The 55 arms operating the suction-valves and those operating the forcing-valves are arranged at an angle of forty-five degrees to each other, so that when a suction-valve is locked the corresponding forcing-valve will be free, and vice 60 versa.

The suction-valves 38 39 are adapted to open downward, and their upper edges rest

against seats formed upon the floor of the valve-chamber. Each of these valves is provided with an extension, 42, rising at an obtuse angle from the body of the valve and having its upper side reduced to form the arc of a circle whose radius is equal to the length of one of the locking arms. Said extensions are preferably constructed to overbalance the body of 75 the valves, but this is not absolutely essential.

70 A light spring presses upon the extension of either suction-valve and serves to instantly close it after same has been opened. The forcing-valves 40 41 open upward, and also have 80 seats formed upon the floor of the valve-chamber. Said forcing-valves are in general shape and construction substantially similar to the suction-valves, except that they open upward and have the tops of their bodies (instead of the 85 tops of the extensions) reduced to the arc of a circle. Beneath the extensions 44 are springs 45, which keep said valves normally closed. In the tops of the valve-chambers are safety-valves 46, whose function is to allow for the 90 escape of air when the latter has been too greatly compressed by the passage of a train of extraordinary length. The piston-head 47 of the pump 15 is adapted to make but a half-stroke. In the side of the pump-casing are 95 two openings, 48 49, which lie directly before and behind said head when the latter is at rest; but when the piston is reciprocated in either direction, one of said openings is covered by the body of the head. The object of 100 this construction is to prevent retardation of movement of the piston-head by the formation of a partial vacuum when the piston is in operation, and consequently to avoid air-cushioning of said head.

105 50^a is the main-line pipe, which in each signal apparatus enters chamber 16 upon one side and chamber 17 upon the other side. Upon either side of the signal apparatus said main-line pipe is provided with an air-chamber, 51. The object of said air-chamber is to diffuse 110 the pulsations caused by the strokes of the pump and render the pressure or exhaust in the pipes and connected apparatus more constant.

115 The operation of the invention is as follows: When a train passes in the direction of the arrow 1, (see Fig. 2,) the front wheel of the engine strikes tappet 7 and throws it in the direction in which said arrow points. The piston 14 and rod 32 are thereby simultaneously thrust forward. The effect of this action is to lock the forcing-valve 40 in chamber 16, free the suction-valve 38, lock the suction-valve 39, and free forcing-valve 41. The air from the pump is thereby forced into chamber 17 and piston 19 started toward the position shown in Fig. 6. At the same time a portion of the air is forced through the main-line pipe at 50^a to the chamber of the next signal apparatus ahead, corresponding to chamber 16, and tends to throw its piston 18 and target 23 to "danger." When the first wheel of the train has passed beyond the tappet 7, the springs 120 130

draw the piston 14 (and tappet) back to normal position. The effect of this is to exhaust the air at the right of the piston-head. As the suction-valve in chamber 17 is locked and the forcing-valve in said chamber opens upward, no air can be drawn from said chamber. On the other hand, the suction-valve in chamber 16 being free the air in said chamber is exhausted to a certain extent, and the air in the main-line pipe 50 rushes in to fill the partial vacuum. Said pipe being connected with the corresponding chamber 17, of the signal apparatus placed at the end of the section in rear of train, and that signal having been left at "danger," the tendency of the exhaust is to draw the wing 19 and target 24 of said rear signal out of sight, or at "safety." As each wheel of the train passes over the tappet 7, an additional quantity of air is forced into chamber 17 and an additional quantity withdrawn from chamber 16, and piston 19 and its target 24 are brought to "danger." Piston 19 and its target 24 of the signal apparatus in rear of train is brought to "safety," and piston 18 and its target 23 of the signal apparatus at next section in front is set at "danger." If a train pass along the track in the direction of arrow 2, the rod 32 is thrown backward, carrying with it the legs 35^b 36^b. This rocks shafts 35 36 in the opposite direction to that already described and reverses the action of the valve-locks. In this case the forcing-valve 41 in chamber 17 is locked and the suction-valve freed, while the forcing-valve in chamber 16 is freed and the suction-valve locked. The passage of the car-wheels over tappet 7 is thereby made to force air into chamber 16 and exhaust it from chamber 17. The effect of this would be to set target 23 to "danger," set target 23 of apparatus in rear of train at "safety," set target 24 at "safety," and set target 24 of next apparatus ahead of train at "danger." The movement of tappet 7 and connected mechanism, after the stroke of a wheel moving in a given direction, is not sufficient to reset the valves. If the valves are all unset, the relative position of the legs 35^b 36^b 36^a and pins 33 34 would be thus:

50 The movement of the tappet 7 corresponding to a quarter-stroke of the piston, would throw pins 33 34 sufficiently forward to make the legs assume this position: 55 so as to lock the suction-valve in one chamber and the forcing-valve in the other. On return-stroke, by action of springs 11 the pins 33 34 return to position first shown, while the legs and connected mechanism are at a stand-still, thus:

60 the movement of rod 32 corresponding to a quarter-stroke of piston. When the wheel moves in an opposite direction it hits tappet 7 and causes the relative positions to be thus: while on the return-stroke it will be thus:

65 32. Thus it will be perceived that the position of the legs, and consequently of the valve-locks, can always be changed by the outstroke but never by the in-stroke, the valves being always set by the first wheel which strikes the tappet in a given direction, and always remaining set until a wheel coming in an opposite direction strikes said tappet.

Having thus described my invention, what I claim is—

70 1. The combination, with the rotary shaft 4 and flanged rail 1, of the tappet 7 extending above said rail, having the top 8 cut away beneath said top, substantially as and for the purpose described.

75 2. The combination, with the shaft 4, of the cross-piece 9, links 10, and elliptic springs 11, arranged substantially as and for the purpose specified.

80 3. The combination of the pump-casing 15, 90 the piston 14, adapted to make a quarter-stroke when the tappet 7 is forced in either direction, the piston-head 47 of a thickness not less than the length of said quarter-stroke, and the orifices 48 49, formed in the pump-casing directly in front and rear of said head 47 when the latter is in normal position, substantially as and for the purposes described.

85 4. The combination, with the pump, of the valve-chest, provided with chambers 16 17, 100 containing suitable pistons for working the targets, the suction-valves 38 39, and forcing-valves 40 41, said suction-valves covering ports connecting, respectively, with opposite extremities of the pump, and said forcing-valves also covering ports connecting, respectively, with opposite extremities of the pump, substantially as described, whereby when the air is forced into one of said chambers it will be exhausted from the remaining chamber, for the purpose set forth.

95 5. The combination, with the forcing and suction valves, of the rocking shafts 35 36, 105 provided with bifurcated levers 35^b 36^b, adapted, when said shafts are simultaneously rocked in a given direction, to free a suction-valve and lock a forcing-valve in one chamber, while simultaneously locking a suction-valve and freeing a forcing-valve in the remaining chamber, as and for the purposes set forth.

110 6. The combination, with the valves and the rocking shafts provided with locking-arms and bifurcated levers, of the reciprocating bar 32, provided with pins 33 34, adapted to engage with the legs of said bifurcated levers, substantially as and for the purposes described.

115 7. The combination of the valve-chest provided with chambers 16 17, and having a target-operating piston, a forcing and a suction valve, and a valve-locking device in each chamber, of a main-line pipe communicating at one end of the valve-chest directly with chamber 17, and at the other end of the chest

directly with chamber 16, substantially as and for the purposes described.

8. The combination of the pump 15, provided with orifices 15 16, and piston 14, having head 47, the superposed valve-chest having chambers 16 17, valves 38 39 40 41, and pistons 18 19, main-line pipe, shafts 20 21, targets 23 24, shafts 35 36, provided with lock-

ing-arms 37 37^a, and bifurcated levers 35^a 36^a, reciprocating bar 32, and mechanism for operating piston 14 and bar 32, substantially as and for the purposes described.
